MAGNETIC SIGNAL DEVICE

Leslie B. Haigh, West Orange, and Franklin A. Stearn, Westfield, N. J., assignors to Federal Telephone & Radio Corporation

Application May 26, 1944, Serial No. 537,510

14 Claims. (Cl. 179—92)

This invention relates to signal devices for telephone and like systems and particularly to such devices of the visual type.

The present invention contemplates the employment of improved features of construction and design adapted for obtaining substantial economies in the cost of production of the component parts and likewise in the assembling thereof to obtain desirable compactness in the assembly so as to economize in material and space requirements. It is further designed to have an improved mode of operation and electrical shielding contributing to greater efficiency, reliability and more satisfactory operation. My device is further of a materially simplified and durable construction and greatly facilitates assembly of the respective parts and proper adjustment thereof resulting in important maintenance economies.

An important feature of the present improvements consists of a simplified single piece frame member of an improved channel form for supporting the parts. This improved channeled frame permits of the closely positioned, or contact, mounting of the units upon a supporting panel and provides a full shielding of the magnet coil as the wall of the channel provides shielding common to adjacent coils. The frame being part of the magnetic circuit is further made with an integrally formed lip in an arrangement providing a pole piece and in addition a support for a bearing piece for the movable armature. The armature thereof is further arranged and pivotally supported with relation to the frame pole piece and likewise to a central core pole of the magnet so as to provide multiple air gaps associated with poles at each side of the pivotal point of the armature. As a result, upon energizing the magnet an attractive force is applied to the armature at opposite sides of its pivot in a manner greatly increasing the torsional pull thereon.

The foregoing and other features and advantages of the present improvements will be more fully understood by reference to the accompanying drawing wherein like reference numerals are applied to the corresponding parts in the several views.

Referring to the drawing:

Fig. 1 is a view partially in front elevation and partially in vertical section illustrating the multiple assembly of the improved signal devices upon a supporting panel;

Fig. 2 is a view of the combined drop and jack

structure in side elevation with the panel and drop shown in section;

Fig. 3 is a vertical cross-sectional view taken on line 3—3 of Fig. 2;

Fig. 4 is a view corresponding to Fig. 2 with the parts shown in the restored position upon inserting the plug connection.

Fig. 5 is a cross sectional view taken on line 5—5 of Fig. 2;

Fig. 6 is a view in side elevation of the magnet and movable armature incorporated in a simplified form of target type of line signal.

Fig. 7 is a similar view of a modification for a trunk line signal assembly.

15 In the preferred embodiment of the invention as shown in Figs. 1 to 5 the improved features are embodied with a combined jack and restoring drop arrangement. Therein the supporting frame and iron of the magnet is formed of a single piece of magnetic material comprising integral upper, lower and side walls 1, 2 and 3 and the turned over end walls 4 and 5. The frame so formed provides an open sided, elongated and rectangular enclosure for the magnet and armature assembly and which in its cross section is of channel formation. With an accompanying arrangement wherein the coil, jack contacts and associated parts are of a width and positioned within the vertical planes defined by the side edges of the frame, the devices in the panel board assembly are positioned side by side with frame to frame engagement, or near engagement, as illustrated in Fig. 1. It accordingly results with advantage, that a full enclosure shielding of each 20 coil is provided wherein the vertical side wall 3 is common in its shielding path to the adjacent coils. Thereby is obtained economy both in space and metal.

Associated therewith is a materially improved 40 supporting and operating arrangement for the armature *a*. In accordance with this feature of the invention, as best shown in Figs. 2, 3 and 4, an integral supporting lip and pole piece 6 is stamped out and bent inwardly from the upper flange and sidewall portion of the channel frame member. This integral lip 6, having a free end, may be of a degree of resiliency providing in the first instance a supporting and clamping member for the bearing piece 7 formed at its inner end

45 with the down turned ears 9 and perforated to receive the pivot pin 8 upon which the armature *a* is pivotally mounted or fulcrumed. After proper adjustment, the bearing piece 7 may be welded or riveted permanently in place. As 50 shown in the improved arrangement the integral

55

lip 6 also operates as a pole piece with relation to the upper surface of the magnet forwardly of its pivotal point and having the normal air gap *d* thereby to apply a supplemental magnetic pull on the armature in addition to the attraction or pull thereon imparted by the pole piece extension *b* of the usual centrally positioned magnetic core acting upon the rearward end of the armature through the air gap *e*. The armature as shown is provided with the usual forward latch extension 10 provided with the detent 11 for normal retaining engagement with the usual hinged drop or signal target 12.

In the construction as disclosed the forward end wall 4 of the magnet frame is provided with threaded apertures to receive the securing screws 14 passed through the countersunk apertures in a shutter mounting plate 15 and apertures in the front panel whereby the magnet frame and plate 15 are secured upon the panel mounting. An additional securing screw is provided countersunk within an aperture in the panel and threaded to the frame end wall. The member 15 may desirably be of vertical channel form with the side flanges apertured at their lower portions to receive the horizontally positioned pivot pin 18 for the drop or shutter 12.

In the assembling of the magnet and associated armature within the frame 1, the coil is mounted upon the usual central core *b* and provided with forward and rearward insulated spacer bushings 20 with the usual coil terminal connectors 21 projected outwardly through apertures in the end wall. The core is secured as by a screw 23. The armature bearing member 7, with the armature pivotally secured thereon, is then assembled through the side opening with its horizontal securing portion resiliently held and secured by the combined lip and pole piece 6 firmly to retain the armature in proper relation to the pole pieces *b* and 6. This arrangement, as will be understood, permits of horizontal adjustment of the bearing piece 7 and the supported armature for properly adjusting the operating relation.

The frame member 1 at its underside and at its rearward portion is formed with a downwardly deflected lip portion 24, (Fig. 5), in similar formation to that of the lip portion 6 and providing a resilient securing lip or flange for the attachment of a jack assembly composed of the usual forwardly extending spring contacts assembled with suitable insulating blocks or spacers.

The jack assembly indicated generally by J is connected by an inverted U bolt 26 providing at its upper end a loop received over the securing lip 24. This permits lateral assembly therewith as will be readily understood after which the jack members are firmly secured by the tightening of the usual clamping nuts 28. In the customary arrangement the upper line contact 29 is provided with an insulating button 30 positioned to engage the forwardly extending restoring spring 32 passing through the panel with the upturned lip 33 positioned to engage the drop for the restoring thereof to latched position upon being elevated by the insertion of the usual line connecting plug 35 as indicated in Fig. 4.

There is thus produced a simplified structural form of combined drop and jack wherein the parts are assembled with ease, with improved accessibility for adjustment and inspection and wherein the parts thereof, including the jack structure, are of a width and positioned to come within the vertical plane of the sidewalls of the frame support 1 as referred to whereby they may

be assembled in close or contacting arrangement. In addition to the advantageous mutual sidewall shielding effect as referred to a desirable compactness in the assembly is permitted which in comparable relation to the standard units as at present employed may be of the order of about three to one of the present standard space requirement thus substantially increasing the operating capacity of a panel board of given space limitations.

While the described structural features are particularly adapted to the disclosed combined drop and jack arrangement it will be understood that certain features thereof may with like advantages be incorporated in a simplified target signal structure as employed in line use indication of switch boards and the like. Such an embodiment is shown in Fig. 6 wherein a magnet and double air gap armature of the same construction is employed but wherein the armature extension, in place of being in the form of a latch or hook is of simple forward extension 40 having an upturned target portion 41 operating to the rear of a suitable panel opening or window 43 and electrically connected in the line in a manner whereby the magnet is energized for the raising of the target when the related line is in use. In this structure 44 indicates a contact of the customarily employed night alarm circuit which is grounded by engagement of the target 40 therewith. A further modification is shown in Fig. 7 employing the improved double pole and air gap feature and a fulcrumed armature with a target type signal as employed for trunk line signalling, wherein the magnet coils as shown are mounted directly to the under side of the frame enclosure 46 which at its front portion is provided with the window 47 and wherein the individual frames for the magnets are omitted as not required for shielding in such assemblies. In this instance the forward pole piece 48 secured to the underside of cover plate 46 may be an elongated bar common to a plurality of magnets as will be understood and the fulcrum bearing piece 49 may be welded to the cover plate 46.

What is claimed is:

1. A magnetically actuated signal device comprising a magnet coil provided with a core, an iron frame enclosure therefor consisting of an open sided channel section enclosing member formed in one piece adapted for multiple unit assembling whereby the sidewall of the frame has a common shielding relation to adjacent coils.

2. A magnetically actuated signal device comprising a magnet coil provided with a core, an iron frame enclosure therefor consisting of an integrally formed elongated open sided frame member of channel section formed in one piece adapted for multiple unit assembling with the sidewall of the frame in common shielding relation to adjacent coils and a pivoted armature supported in the frame and in cooperative relation to the magnet core and frame.

3. A magnetically actuated signal device comprising a magnet coil provided with a core, an iron frame enclosure therefor consisting of an open sided frame member of channel section formed in one piece adapted to receive the coil therein and for multiple unit assembling with the sidewall of the frame in common shielding relation to adjacent coils, said frame member extending forwardly of the coil and having within its forward extension a pivoted armature in

cooperative relation to the magnet core and to the frame and a movable signal element controlled by the armature.

4. A magnetically actuated signal device comprising a magnet coil provided with a core, an iron frame support therefor consisting of an open sided frame member of channel section supporting the coil therein and adapted for multiple unit assembly with the side wall of the frame in common shielding relation to an adjacent coil, said frame having an extension forwardly of the coil and formed with an inwardly deflected pole piece portion, an armature pivotally supported in said extension in cooperating relation to said pole piece and to the magnet core, and a movable signal element operatively associated with the armature whereby the latter controls the movement thereof.

5. A magnetically actuated signal device comprising a magnet coil provided with a core, an iron frame support for the coil, an armature supported inside the confines of the frame and by an integral part thereof and fulcrumed to have an air gap relative to both the core and the frame for unidirectional movement by magnetic attraction on energizing of the coil and signal means controlled by the armature.

6. A magnetically actuated signal device comprising a coil provided with a core, an iron frame enclosure for the coil of open side channel section, said iron frame having an extension forwardly of the coil, an armature supported inside the confines of the frame and by an integral part thereof and fulcrumed in magnetic air gap relation to both the core and the iron frame for unidirectional movement by magnetic attraction on energizing of the coil and said coil and armature being contained within the frame to permit of multiple assembly of the units with the side-wall of the frame in mutual shielding relation to an adjacent coil.

7. A combined drop and jack structure comprising a magnet coil provided with a core, a supporting frame member therefor consisting of an open sided member of channel section adapted for multiple unit assembly with the side wall of the frame in mutual shielding relation to adjacent coils, said frame member extending forwardly of the coil and having within its forward extension a pivoted armature in cooperative relation to the magnet core and to the frame, a panel support to which the frame is secured, a shutter drop pivotally supported at the front of the panel, a latch extension on the armature forwardly extending through the panel and formed with a detent to engage the drop, said frame being formed on its end side with a vertical deflected lip portion, a jack spring assembly provided on its upper surface with an attached loop for engaging the deflected lip portion said jack being provided with a forwardly extending restoring spring and adapted for restoring engagement with the drop responsive to insertion of a line extension plug.

8. A magnetically actuated signal device comprising a magnet coil provided with a core, an iron frame support therefor, said frame having an extension forwardly of the coil and formed with an inwardly deflected pole piece portion, an armature pivotally supported inside said iron frame support and by an integral part thereof in cooperating relation to said pole piece and to the magnet core, and a movable target element controlled by the armature.

9. A magnetically actuated signal device comprising a magnet coil provided with a core, an iron frame support therefor, said frame having

an extension forwardly of the coil and formed with an inwardly deflected pole piece portion formed integrally therewith, an armature bearing member supported by the pole piece, an armature pivotally supported inside said iron frame in the bearing member in magnetically coupled relation to said pole piece and to the magnet core and a signal target controlled by the armature.

10. A magnetically actuated signal device comprising a magnet coil provided with a core, an iron frame support therefor, said frame having an extension forwardly of the coil and formed with an inwardly deflected pole piece portion, an armature bearing member slidably secured by the pole piece portion, an armature pivotally supported by the bearing member in magnetically coupled relation to said pole piece and to the magnet core to be rotatably moved thereby by attraction at opposite sides of its fulcrum and a signal target controlled by the armature.

11. A magnetically actuated signal device comprising a magnet coil provided with a forwardly extended core, an iron frame support therefor, said frame having an extension forwardly of the coil formed with an inwardly deflected pole piece, a bearing member slidably secured by the pole piece, an armature pivotally supported by the bearing in magnetically coupled relation to the under side of the pole piece and to the core and at opposite sides of its fulcrum and a signal element controlled by the armature.

12. A combined drop and jack structure comprising a magnet coil having a forwardly extended core, a frame support therefor of magnetic material, said frame being extended forwardly of the coil and of open side channel section, a pole piece integrally formed on the frame by inward deflection of a portion of the upper wall thereof forward of the coil, a bearing member secured to the pole piece and formed with bearing ear portions, a pin carried by the ear portions, an armature pivoted on the pin to extend forwardly and rearwardly thereof in magnetic coupled relation to the pole piece and the core at opposite sides of its fulcrum, a latch extension on the armature provided with a detent, a hinged drop engaged by the detent, an integral securing lip formed on the frame under wall and a jack assembly provided with a loop for lateral assembly with the lip and said jack assembly coil and armature members having a width to be non-extending beyond the vertical planes defined by the sides of the frame to permit of multiple close assembling wherein the sidewall of the frame has a mutual shielding relation to adjacent coils.

13. A combined drop and jack structure comprising a magnet coil having a forwardly extended core, a frame support therefor of magnetic material, said frame being extended forwardly of the coil, a pole piece integrally formed on the frame by inward deflection of a portion of the upper wall thereof forward of the coil, a bearing member slidably secured by the pole piece and formed with bearing ear portions positioned in a vertical plane intermediate of the core and frame pole, a pin carried by the ear portions, an armature pivoted on the pin to extend forwardly and rearwardly thereof in magnetic coupled relation to the pole piece and the core at opposite sides of its fulcrum, a latch extension on the armature provided with a detent, a hinged drop engaged by the detent and a jack assembly secured to the frame support.

14. A combined drop and jack structure comprising a magnet coil having a forwardly extended core, a frame support therefor of mag-

netic material, said frame being extended forwardly of the coil, a pole piece integrally formed on the frame by inward deflection of a portion of the upper wall thereof forward of the coil, a bearing member slidably secured by the pole piece and formed with bearing ear portions, a pin carried by the ear portions, an armature pivoted on the pin to extend forwardly and rearwardly thereof in magnetic coupled relation to the pole piece and

the core at opposite sides of its fulcrum, a latch extension on the armature provided with a detent, a hinged drop engaged by the detent, an integral securing lip formed on the frame under wall and a jack assembly provided with a loop connector for lateral assembly with the securing lip.
